SAFETY TILE SECTION

Frederick W. Cotterman, Dayton, Ohio, assignor
of one-half to Bessie D. Apple, Dayton, Ohio

Application March 17, 1939, Serial No. 262,540

4 Claims. (Cl. 210—164)

This invention relates to a tile section which is particularly effective in catching leaves, birds nests, and the like, which are washed out of roof gutters, down the spouting and into the underground tiling into which the spouting empties.

In many sections of the country the rain water from roofs is collected and conveyed to cisterns for household use. This practice is sometimes due to the difficulty of getting a water supply 10 otherwise, and sometimes due to the fact that in some geographical locations the water pumped from wells is so highly charged with lime as to render it unfit for most household uses.

In other cases the water collected from roofs 15 is merely conveyed thru jointed tiling to a stream or other place of disposal. In the first case it is more important for sanitary reasons to strain insects, leaves, birds nests and other foreign matter from the water, but in either event it is im- 20 portant for the reason that frequent stoppages occur in the tiling which necessitates frequent digging up of the lawn or shrubbery beds with its consequent mess and annoyance.

To overcome the foregoing trouble, screens 25 have been used in the top ends of the down spouts where they join the gutters, and these work satisfactorily if they are frequently given attention. The leaves, however, soon pack around the screen and clog it, making it necessary to take a ladder and climb to the place of 30 stoppage and remove the obstruction, which is at its best an undesirable performance.

In other cases, strainers, or filters are incorporated in and near the lower ends of down- 35 spouts, and these have found some favor, but they have the fault that, being above the ground line, they are not only unsightly, but may under certain conditions, freeze up and defeat their purpose. Furthermore, being of metal and ex- 40 posed, such devices rust and deteriorate rapidly.

Since it is quite common practice to use, for the first section of the tiling, an elbow tile, into the bell end of which the bottom end of the downspout is cemented, it is an object of this 45 invention to so construct and arrange a first section of tiling, which may be a section of vitreous or cast iron tiling, that the major portion thereof will be below the ground level where it will not present an unsightly appearance, nor 50 be exposed to freezing, and will be least subject to physical damage and deterioration, then incorporate in this first section an easily accessible strainer which may be readily removed, emptied and replaced.

55 Where rain water is collected from roofs and

conducted to cisterns thru tiling, it is highly im- 5 portant that the lid thru which the strainer is to be removed for emptying, the joint between the lower end of the downspout and the tile sec- 10 tion, and the joints between succeeding sections, be substantially perfect, in order that ground worms, insects and dirt be excluded from the cistern, and it therefore becomes another object of this invention to so construct the device that such perfect joints may be readily made at the 15 several places indicated.

Where, however, the joints are made as above 20 stated, and the cistern has no overflow tile, it has happened that when a cistern was already 25 completely filled there came an unusual and ex-cessive downpour of rain, from which water built up in the downspouts high enough to overflow the roof gutters, in which case there was suffi- 30 cient head in the cistern to crack the walls thereof, and it therefore is another object of 35 this invention to provide a relief means for such excessive pressure without the addition of mech- 40 anism which might get out of order and without 45 having any opening thru which insects might 50 enter.

Further meritorious features and advantages 55 will become apparent from the following descrip- 60 tion when read with reference to the drawing, 65 wherein,

Fig. 1 is a vertical cross section thru the 70 device,

Fig. 2 a top plan view.

Figs. 3 and 4 show vertical cross sections thru 75 modifications.

Similar numerals refer to similar parts thru- 80 out the several views.

Imbedded in the earth 10, Fig. 1, is a section 85 of tiling in which my invention is embodied. It comprises a vertically extending cylindrical body portion 12 with a short laterally extend- 90 ing outlet portion 14 of a size corresponding to the lateral sections 16 into the bell 18 of which it extends, having a cemented joint 20.

Preferably about at the ground line 22 the 95 body of the section is enlarged to a diameter 24 thereby providing a shoulder 26 upon which rests a sheet metal ring 28 having an outer diameter which will enter the inside 30 of the part 24 freely and an inner diameter which will receive a cylinder 32 of screening which is open 100 at the top and may be secured to the ring at the upper edge by soldering or other suitable means. A heavy wire handle 34 has its ends 105 extended thru holes in the ring 28 and is soldered or otherwise fastened therein. A bottom 36 may 110

ticularly where the earth was shrunk away from the outside leaving the walls unsupported.

It will be obvious that the use of the device is justified to provide cleaner water in cisterns for household use, to obviate digging up of lawns to remove leaf obstructions, to retard freezing of wet leaves in the strainer basket, and to prevent undue pressure on cistern walls from excessive head in the downspouting when the cistern is full. 10

Having thus described my invention, I claim—

1. A device of the character described, comprising a section of tiling adapted to be imbedded for the greater portion of its length in the earth and having a vertical hollow cylindrical body with open upper end and a laterally extending hollow cylindrical outlet at its lower end, said cylindrical body having a hollow interior which enlarges abruptly in size near its upper end approximately at the ground line thereby providing a shoulder in its interior diameter, a cylindrical screen basket of smaller diameter than the inside of the lower portion of the cylindrical body having a sheet metal ring around its open top resting on said shoulder and a handle, a lid resting on the said open upper end of the cylindrical body and having a rim extending downwardly to fit freely therein, said rim being provided with a series of notches extending from the lower edge nearly to the upper edge, and an inlet elbow integral with said cylindrical body and extending laterally then upwardly therefrom, the upper end being enlarged to receive a downspout, the lateral opening of said elbow entering said cylindrical body between the top of said shoulder and the lower edge of said rim. 15 20 25

2. In a device of the character described, a tile section comprising a vertical hollow middle portion with an outlet elbow of smaller diameter than said middle portion extending laterally from the lower end and an upper portion with open top and of larger bore than the middle portion extending vertically from the upper end thereby forming a shoulder in the inner diameter of the tile section intermediate its ends, a screen basket of smaller diameter than the inside of the middle portion having a flange at its open top resting on said shoulder, a lid resting on the upper open end of the upper portion and having a rim slidably freely into the inside of said upper portion and provided with notches extending therethru, and an inlet elbow integral with said upper portion having an opening thereto between the said shoulder and said rim, said elbow having a hollow interior which enlarges abruptly in size near the upper end to receive a downspout, and form a shoulder therefor. 40 45 50

3. A safety tile section comprising, a vertical hollow body open at the top and with an outlet at its lower end and a bore which enlarges abruptly near its upper end thereby forming a shoulder on the inside diameter intermediate the ends of the section, a perforate basket of smaller diameter than the inside of the body having a flange at its upper open end of larger diameter resting on said shoulder, a lid resting on the upper open end of the hollow body having a rim extending freely downward into its interior, the rim being cut away at intervals leaving sections of rim standing, and an inlet portion integral with the hollow body having an opening extending laterally into said hollow body between said shoulder and said rim. 60 65 70

4. A safety tile section comprising, a hollow

be made of the same screening as the cylinder 32. The basket comprising the parts 28, 32, 34 and 36 should be entirely of non-corrosive material, copper being suitable. The assembled basket may be referred to by the numeral 38.

A removable lid 40 rests on the upper edge of the cylinder 24. The joint 42 between the lid and cylinder should be ground or otherwise finished to exclude ants and other small insects.

- 10 14 A flange 44 on the bottom of the lid extends downwardly into the cylinder and should fit with sufficient freedom to permit easy removal of the lid. A knob 46 is provided for removing and replacing the lid.
- 15 Intermediate the shoulder 26 and the bottom of the rim 44 an inlet opening 48 extends first laterally then upwardly within the inlet elbow 50 which is integral with the cylinder 24. The elbow 50 is enlarged at the upper end to form 20 the bell 52 into which the downspout 54 extends to a shoulder 56. A joint of cement 58 secures the downspout in the bell 52.

Extending thru the rim 44 are a series of notches 60. These notches extend from the bottom of the rim upwardly almost to the top edge 42. If and when pressure builds up from below sufficient to raise the lid, the upper edges of the notches 60 will rise above the line 42 to provide an outlet which remains open only 30 as long as there is an overflow.

The embodiment shown in Figs. 1 and 2 will be preferred where the fall in the tiling is limited. Where it is not so limited the cylindrical portion 12 instead of having a lateral outlet portion 14 for connection to a straight tile section 16 laid horizontally may instead be merely reduced in diameter at the lower end as at 62 Fig. 3 and cemented as at 64 in the bell 66 of a short turn elbow 68. The succeeding lateral sections 40 will necessarily be from six to ten inches deeper below the top of the ground level than with the structure Fig. 1, but where there is plenty of fall this may not be an objection.

Fig. 4 shows an application of the form of section shown in Fig. 3, but where the lateral tiling is deeper in the earth. In such a case several standard tile sections 16 may be added vertically, then by means of a standard elbow turned in a lateral direction.

50 In operation, any leaves, birds nests, spiders, etc., washed by a rain from the roof gutter into the downspout 54 will be carried thru the elbow 50 into the basket 38, the water passing thru freely to the cistern or other outlet. Once or 55 twice a year, the lid 40 should be lifted, the basket raised by the handle 34, emptied and replaced.

If emptying of the basket is neglected until it becomes packed solidly and quite to the top, a heavy rain may have to lift the lid 40 and bring the overflow notches 60 into action. The washing away of ground in the immediate vicinity will give an indication of the stoppage.

65 The overflow notches will function in the same manner if a heavy rain falls after a cistern having no overflow tile is quite full. If the device were without any pressure relief means, and assuming a cistern 10 feet deep with 70 a distance from the top of the cistern to the roof gutter of 20 feet, this head of 30 feet would cause a pressure against the cistern wall near its bottom of nearly a ton lateral per square foot of wall. Under these circumstances cistern walls 75 have been known to break under the strain, par-

body of rust proof material open at the top and bottom and adapted to be partly imbedded in the earth, the bottom end being adapted for connection with other tile sections, a lid covering 5
the open top and held down thereon solely by its own weight, whereby said lid may be raised freely by pressure from below, said hollow body having a basket support formed on the inside intermediate the top and bottom, a rust proof basket having perforated side walls spaced considerably away from the inside of the said hol-

low body and a flange around the open top of the basket extending outwardly and resting on said basket support, said flange being of a size which may be freely withdrawn thru said open top of said hollow body, and so formed as to hold the basket sides spaced away from the walls of the body, and an inlet neck integral with the hollow body, the inlet opening in said neck entering the hollow body above said basket flange and below said lid. 10

FREDERICK W. COTTERMAN.
